[57] CLAIM

The ornamental design for a baby bottle prop, as shown.

DESCRIPTION

FIG. 1 is a perspective view of a baby bottle prop, showing my new design, the broken line showing of the baby bottle is for illustrative purposes only and forms no part of the claimed design;

FIG. 2 is a side elevational view thereof, the opposite side being identical thereto; and

FIG. 3 is an end elevational view thereof, the opposite end being identical thereto.

The bottom of the baby bottle prop is substantially plain and unornamented.
